UNITED STATES PATENT OFFICE.

GEORGE DONGES, OF PHILADELPHIA, PENNSYLVANIA.

IRONING-TABLE.

1,074,778.

Specification of Letters Patent.

Patented Oct. 7, 1913.

Application filed March 15, 1912. Serial No. 683,942.

To all whom it may concern:

Be it known that I, GEORGE DONGES, a citizen of the United States, residing at Philadelphia, in the county of Philadelphia and State of Pennsylvania, have invented 5 certain new and useful Improvements in Ironing-Tables, of which the following is a specification.

This invention relates to that class of 10 ironing tables wherein an ironing-board and a table top are provided and constructed and related to each other so that they may be adjusted to conceal the ironing-board beneath the table top and to expose the ironing-board 15 above the table top for use.

The object of my invention is to provide 20 an ironing-table of novel, simple and efficient construction, having provision whereby an ironing-board may be properly supported and readily raised from its concealed 25 position when that portion of the table top covering the ironing-board is removed, whereby the ironing-board may be maintained in the raised position and whereby 30 the ironing-board may be readily lowered.

A further object of the invention is to 35 construct the ironing-board in two parts hinged together and to provide an adjustable brace to permit one end of the board to 40 be folded down against one end portion of the table frame when the board is not in use and to support the hinged end of the board 45 when in use.

The invention consists in the novel 50 combinations of parts which will be hereinafter pointed out in the claims after being described in the specification.

In the accompanying drawings, illustrating 55 my invention: Figure 1, is a side elevation of my improved ironing table, showing the ironing-board in position for use. Fig. 2, is a transverse section, on line 2—2 of Fig. 1. Fig. 3, is an end view of the ironing-table, showing the ironing-board out of use and concealed beneath the table top. Fig. 4, is a plan view of the ironing-table with the parts in the position shown in Fig. 3. Fig. 5, is a plan view of the ironing-table with the parts in the position shown in 60 Fig. 1.

Referring to the drawings, the table frame 65 comprises the supporting legs 3, the longitudinal bars 4 and the transverse bars 5, the ends of the bars 4 and 5 being secured to the legs 3.

Mounted on the table frame is the table

top comprising a part 6 secured to the table frame and a part 7 hinged at 8 to the part 6 and movable on the hinge 8 from the position shown in Fig. 3 to the position shown 60 in Fig. 2 and back again.

The ironing-board 9 is concealed beneath the part 7 of the table top when the part 7 is in the position shown in Figs. 3 and 4; and the ironing-board 9 comprises a body 65 portion 10 and an end portion 11 hinged at 12 to the body portion 10. The end of the body portion 10 adjacent the hinge 12 is mounted on and secured to the upper ends of two vertical bars 13, leaving the other 70 end of the body portion 10 free to be surrounded by skirts, shirts and the like while being ironed upon the board 9.

The bars 13 are dove-tail shape in cross section and are slidably fitted to two similarly shaped guideways 14 formed between the bars 15 of two pairs of bars, as shown. The bars 15 of one pair are secured to one of the end bars 5 of the table frame, and the bars 15 of the other pair are secured to a 80 transverse bar 16 which extends between one bar 4 of the table frame and another longitudinal bar 17 extending between and secured to the transverse bars 5. The lower portions of the bars 13 are connected by a 85 horizontal brace bar 18.

From the construction just described it will be seen that the ironing-board may be readily raised and lowered. When the board 9 is in the down position it rests in 90 depressions in the end bars 5 of the table frame to permit the part 7 of the table top to be moved to the position shown in Figs. 3 and 4 providing a table with an uninterrupted top for ordinary kitchen use. 95

In order to raise and lower the ironing-board 9, when the part 7 is in the position shown in Figs. 1, 2 and 5, I provide the following: Extending between and mounted to turn in one of the bars 4 and the bar 17 is a 100 horizontal shaft 19 the outer end of which is provided with a projecting arm 20 by means of which the shaft may be turned by hand. Secured to the shaft 19 is the hub or collar 21 of a cam arm 22. The cam arm 105 22 is adapted to act against the bottom of the ironing-board 9 and it is provided with a curved body portion and a flat end portion 23, as shown. The curvature of the cam arm 22 is such that when the arm 20 is 110 moved from the position shown in Fig. 4 to the position shown in Fig. 5, the ironing-

board will be raised to the position shown in Figs. 1, 2 and 5, and that when the arm 20 is moved back to the position shown in Fig. 4, the board 9 will be lowered to the position shown in Figs. 3 and 4. By providing two bars 13 and locating the cam arm 22 between the bars 13 and between the guideways 14 therefor I am enabled to raise and lower the ironing-board with ease.

5 When the ironing-board is in the raised position, it rests upon the flat end portion 23 of the cam arm 22 and the cam arm 22 rests against the adjacent bar 13 which supports the ironing-board. The flat portion 23 prevents liability of the cam arm 22 being accidentally turned, and the flat portion 23 is slightly past the center of the shaft 19 toward the bar 13 against which the cam arm 22 rests when the ironing-board is in the raised position, so that any downward pressure upon the ironing-board will tend to force the cam arm 22 more firmly against the bar 13 and prevent the accidental lowering of the ironing-board when in use.

10 When the ironing-board is in the raised position for use, the hinged end portion 11 thereof is in the horizontal position shown in Figs. 1 and 5 and it is maintained in such position by a brace rod 24 inclined from the end portion 11 to one of the bars 5 of the table frame. The lower, inner end of the brace 24 is inserted into an opening 25 in the bar 5, and the upper, outer end of the brace extends through and is slidably fitted 15 to a head 26 which is swiveled on the bottom of the end portion 11. Prior to the lowering of the ironing-board, the brace 24 is disengaged from the opening 25; and when the ironing-board is lowered, the end portion 11 thereof is moved on the hinge 12 down to the position shown in Figs. 3 and 4 adjacent the

end bar 5 of the table frame, and the brace 24 is adjusted into the position shown in Figs. 3 and 4 with one end of the brace resting in an eye 27 projecting from the adjacent bar 5 of the table frame. The adjustment of the brace 24, as just described is permitted by the turning of the swiveled head 26 and by the sliding of the end of the brace within the head 26. When the ironing-board is again raised, the brace 24 is adjusted back to the position shown in Figs. 1, 2 and 5 to support the hinged end portion 11 of the board.

I claim:

1. In an ironing table, the combination of a table frame, a vertically-movable ironing-board, means on said frame for supporting and guiding said board, a shaft journaled on said frame, an operating arm on said shaft, and a cam carried by said shaft and having a curved portion adapted to raise said board and a flat portion adapted to maintain said board in the raised position.

2. In an ironing table, the combination of a table frame provided with a vertical guideway, a vertically-movable ironing-board, a bar slidably fitted to said guideway and supporting said board, a shaft journaled on said frame, an operating arm on said shaft, and a cam carried by said shaft and operative to raise said board and maintain it in the raised position, said bar forming a stop for said cam when said board is in the raised position.

In testimony whereof I affix my signature in presence of two witnesses.

GEORGE DONGES.

Witnesses:

S. I. HARPER,
A. V. GROUPE.
